FIG. 2

INVENTOR
VINCENT BENDIX
BY *J.W. McConkey*
ATTORNEY

UNITED STATES PATENT OFFICE.

VINCENT BENDIX, OF CHICAGO, ILLINOIS, ASSIGNOR TO BENDIX BRAKE COMPANY, OF CHICAGO, ILLINOIS, A CORPORATION OF ILLINOIS.

BRAKE MECHANISM.

Application filed April 7, 1926. Serial No. 100,257.

- This invention relates to brakes, and is illustrated as embodied in several types of automobile brakes and operating mechanism therefor. An object of the invention is to 5 provide novel and simple self-equalizing operating mechanism for the brake, preferably including a toggle acting on the shoes, the mechanism in the forms illustrated being especially well adapted for use on brakes for 10 front or other swivelled wheels. The illustrated forms have the further advantage that they may be used for applying a floating or "servo" shoe which moves with the drum to apply another shoe:
- 15 Other important minor features of novelty include various improvements in the brakes, to adapt them for use with controls of the sort described, and to other novel combinations of parts and desirable particular 20 constructions shown in the accompanying drawings, in which:
- Figure 1 is a vertical section transversely through one front brake and through associated parts;
- 25 Figure 2 is a vertical section through the brake on the line 2—2 of Figure 1, showing the brake shoes in side elevation;
- Figure 3 is a view corresponding to Figure 2, but showing a different brake;
- 30 Figure 4 is a view corresponding to the upper part of Figure 2 and of Figure 3, but showing a third brake; and
- Figure 5 is a partial section on the line 5—5 of Figure 4, and showing the shiftable 35 anchorage of this type of brake.
- The arrangement shown in Figure 1 includes a drum 10 rotating with a wheel (not shown) mounted on the spindle 12 of a knuckle 14 swivelled, by a king pin 16 or 40 the like, at one end of a front axle 18 which, with a rear axle (not shown), supports a suitable chassis frame 20 through the usual springs 22. At the open side of the drum is arranged a stationary support such as a 45 backing plate 24.
- The brake illustrated in Figures 1 and 2 includes a reverse shoe 26 anchored on a pivot 28 on backing plate 24, and a pair of shoes 30 and 32 pivotally connected at 34 and 50 anchored on a pivot 36. Pivot 28 for shoe 26 passes through a relatively large opening in the web of shoe 32, while pivot 36 passes through a relatively large opening in shoe 26, thus in effect overlapping shoes 26 and 32. Shoe 32 is held by a spring 38 against an 55 adjustable stop 40, while shoes 26 and 30 are urged by a connecting spring 42 against adjustable eccentric stops 44.
- The brake may be applied by suitable means, such as a shaft 46 operated by an 60 arm 48 and slidably and universally supported on frame 20 by a support 50, acting through a novel toggle mechanism to force shoes 26 and 30 apart toward the drum against the resistance of spring 42. The 65 outer end of shaft 46 is flattened and swivelled by a pin 52 between two outwardly cylindrical connecting devices 54 received in a cylindrical cross bore in the end of a shaft 56 journaled in a bracket 58 secured to the 70 backing plate.
- Shaft 56 has an extension 60, preferably integral, to which is fixedly secured an arm 62 operating a tension link 64 connected to the knuckle of a toggle including links 66 75 and 68 connected respectively to the ends of shoes 26 and 30.
- The brake of Figure 3 differs from the one just described, in that there are only two shoes 130 and 132, corresponding in a general way to shoes 30 and 32, and which are pivotally connected at 134 and pivotally anchored at 136. A spring 138 holds shoe 132 against a stop 140 until overcome by movement of shoe 130, while a spring 142 tensioned between the shoes urges shoe 144 80 against another stop 130.
- The brake of Figure 4 is like that of Figure 3, except that shoe 232 is not anchored by being mounted on a pivot. In this brake, 90 if the drum is turning counter-clockwise, the cut-out or concave end of shoe 232 anchors against the journal bearing portion of bracket 58, which is made somewhat longer for that purpose, while if the drum is turning 95 clockwise the rounded end of shoe 230 anchors against an arcuate or concave flange 244 on the opposite end of the bracket. This brake is intended to be so arranged that the drum is turning counter-clockwise in Figure 100 4 when the vehicle is moving forward (as is also true of Figures 2 and 3), so that normally shoe 232 does not leave its anchorage when the brake is applied, shoe 230 turning

with the drum to overcome spring 138 and force shoe 232 against the drum.

While several illustrative brakes have been described in detail, it is not my invention to limit the scope of the invention to those particular brakes, or otherwise than by the terms of the appended claims.

I claim:

1. Brake mechanism comprising, in combination, a swivelled wheel having a brake with adjacent separable ends, a short shaft between said ends swivelling with the wheel and having an arm at its outer end and a cross bore in its inner end substantially at the swivelling axis of the wheel, an operating shaft having a connecting device in the cross bore, and a brake-applying toggle linked to said arm.
2. Brake mechanism comprising, in combination, a swivelled wheel having a brake with adjacent separable ends, a short shaft between said ends swivelling with the wheel and having an arm at its outer end and having its inner end substantially at the swivelling axis of the wheel, an operating shaft universally-jointed to the end of the short shaft, and a brake-applying toggle linked to said arm.
3. Brake mechanism comprising, in combination, a swivelled wheel having a brake with adjacent separable ends, a short shaft between said ends swivelling with the wheel and having an arm at its outer end and having its inner end substantially at the swivelling axis of the wheel, an operating shaft universally-jointed to the end of the short shaft, links pivoted to the ends of the brake and extending toward the axis of the wheel and pivoted together to form a toggle, and a connecting link extending from the toggle to said arm.
4. Brake mechanism comprising, in combination, a drum, a fixed support including a journal bearing, a friction device anchoring at one end on the support when the drum is turning in one direction and anchoring at the other end on the support when the drum is turning in the other direction, a shaft in the bearing having an arm at its end, and toggle links connecting said arm to the ends of the friction device.
5. Brake mechanism comprising, in combination, a drum, a fixed support including a journal bearing, a friction device anchoring at one end on the support when the drum is turning in one direction and anchoring at the other end on the journal bearing when the drum is turning in the other direction, a shaft in the bearing having an arm at its end, and toggle links connecting said arm to the ends of the friction device.
6. Brake mechanism comprising, in combination, a drum, a support having a journal bearing at one end and a flange at the other end, a friction device anchoring on the flange when the drum is turning in one direction and on the bearing when the drum is turning in the other direction, a shaft in the bearing, and means operated by the shaft for forcing the unanchored one of said ends against the drum.
7. Brake mechanism comprising, in combination, a drum, a support having a journal bearing at one end and a flange at the other end, a friction device anchoring on the flange when the drum is turning in one direction and on the bearing when the drum is turning in the other direction, a shaft in the bearing, and connections from the shaft to said ends extending between the flange and the bearing.
8. Brake mechanism comprising, in combination, a drum, a support having a concave flange at one end and a rounded bearing at the other end, a friction device having a rounded end arranged to anchor in the concave flange when the drum is turning in one direction and having a concave end arranged to anchor on the bearing when the drum is turning in the other direction, a shaft in the bearing, and means operated by the shaft for forcing the friction device against the drum.
9. Brake mechanism comprising, in combination, a drum, a support having a concave flange at one end and a rounded part at the other end, a friction device having a rounded end arranged to anchor in the concave flange when the drum is turning in one direction and having a concave end arranged to anchor on said part when the drum is turning in the other direction, and means for forcing the friction device against the drum.

In testimony whereof, I have hereunto signed my name.

VINCENT BENDIX.
